UNITED STATES PATENT OFFICE.

CHARLES R. B. CLAFLIN, OF EAST HARTFORD, CONNECTICUT, ASSIGNOR, BY MESNE ASSIGNMENTS, TO THE SIKO-LITE CORPORATION, OF MERIDEN, CONNECTICUT, A CORPORATION OF CONNECTICUT.

HEADLIGHT.

Application filed September 18, 1924. Serial No. 738,551.

My invention relates to improvement in bulbs in head lights in which the rays of light are refracted and dissociated to prevent dazzling effect.

5 The main object of my invention is to reduce glare of headlights without deduction in luminous flux of the projected beam. My method is to render sections of the reflector bright with dark spaces between. My 10 principles are: to place reflecting material upon the bulb in such a manner that none of the direct rays from the filament are visible; to place reflecting material upon the bulb in such a manner that it does not prevent the 15 reflected rays from the reflecting material from reaching the reflector; to locate the filament at the spherical center of the bulb; to have the internally reflected rays of the bulb parallel the direct rays from the filament; to direct the rays from the filament 20 that would be lost in the upper hemisphere into the projected beam of the reflector; to use high reflecting material.

I should note that the lamp is of particular advantage when used on automobiles as well as other purposes.

It is within bounds of possibility as may be inferred that some of the features of my invention can be used with equal advantage 30 in other circumstances; I have a number of other motives in view although my primary and principal object is to prevent sudden blindness against accident.

There are other features of novelty and 35 advantage which will be discussed at length in the following description, wherein I will outline in detail several of the many features of embodiment of the invention which I have selected for illustration in the drawings accompanying and forming a part of 40 the present specification.

This disclosure is made to enable those skilled in the art to practice the invention; I am not restricted thereto, I may obviously 45 depart therefrom in many respects within the scope of the invention defined by the claims following the said description for as I have observed in effect the invention comprises certain broad relations.

50 Referring to the said drawings:

Fig. 1 is a front elevation of the head light;

Fig. 2 is the side elevation as seen from the right of Fig. 1 with the reflector in section;

Fig. 3 is a cross section of the bulb 3 on line A—A;

Fig. 4 is the light bulb covered with reflecting material and one light opening;

Fig. 5 is a modification of the bulb 3 in Fig. 2;

As shown the illuminator comprises in its makeup a light 1 in the bulb 3 having attached thereto a reflecting material 4 and a reflector 2. These may be used in different forms.

The primary feature is the reflecting material which I have illustrated and shown in each figure as 4. This material is laid upon or attached to the bulb or container 3 and may be composed of silver or other substance and can be translucent or opaque, it may be protected with a secondary material or coating.

To prevent the direct rays from the primary light from being projected I have covered the end of the bulb with the reflecting material 4, the remaining portion of the bulb I have placed the reflecting material in one or more stripes, but do not confine myself, I may use disks or other forms or may leave it plain. Between the stripes the rays flow and are collected and refracted in a manner most suitable for the effect desired.

One preferable form of construction I have placed the stripes of the reflecting material on the bulb in alternating radial sections that the refracted rays may pass out of the bulb unobstructed as in Fig. 3 dotted line B. I consider an important feature resides in the alternate sections of the reflecting material 4 and light transmitting spaces 6 around the bulb or light container as it prevents solid glare by diffusing the rays. Another important feature is covering the end of the bulb or container with reflecting material which not only renders the primary light invisible but also refracts the rays against the reflector which would be otherwise of little use.

An important feature is the combined utilization of the rays from the reflecting material on the bulb in conjunction with the primary light rays, as dotted lines B and C, Fig. 3.

To fully utilize the refracting power of the bulb I prefer to deposit a brilliant reflecting material on the bulb as silver, but do not confine myself.

By covering the bulb in whole with reflecting material the rays of light are collected in mass and may be projected in one direction through an opening, as Fig. 4.

5 The dotted line C Fig. 2 illustrates the limit of the direct rays from the primary light upon the reflector.

What I claim is:

1. In a headlight bulb, a disk of reflecting material on the forward end thereof placed symmetrically with respect to the longitudinal axis of the bulb, an odd number of evenly spaced stripes extending back from said disk and parallel to said axis, each stripe being diametrically opposite a space between two such stripes, and a lighting filament.

2. In a headlight bulb, a disk of reflecting material on the forward end thereof placed symmetrically with respect to the longitudinal axis of the bulb and covering but a limited portion of the bulb, an odd number of evenly spaced stripes extending back from said disk and parallel to said axis, said stripes being slightly narrower than the spaces therebetween, and a light filament positioned at the longitudinal axis of the bulb.

3. As a new article of manufacture, a bulb for headlights having a disk of reflecting material applied thereon at its forward end and symmetrically placed with respect to the longitudinal axis of the bulb, an odd number of evenly spaced stripes extending

back from said disk parallel with said axis and applied in like manner as said disk, said stripes being slightly narrower than the spaces therebetween, and a lighting filament symmetrically placed with respect to said longitudinal axis.

4. In a headlight the combination of a bulb and a reflector, a reflector coating applied as a disk to the forward end of the bulb, said disk having reflecting arms extending back therefrom parallel to the longitudinal axis of the bulb, said arms ending at points diametrically opposite the outer edge of said disk.

5. In a bulb containing a lighting filament at its spherical center, sides of the bulb coated with stripes of reflecting material parallel with the axis of the bulb, separated with clear spaces in which the center line of the stripes of reflecting material is approximately 180° from the center line of the clear spaces, on the opposite sides.

6. In a headlight, the combination of a bulb and a reflector, the bulb coated on the end with reflecting material having arms of reflecting material extending on the sides nominally parallel with the axis of the bulb with clear spaces between, said arms diametrically opposite the clear spaces and cut off at the point diametrically opposite the outer edge of the reflecting end.

In testimony whereof I affix my signature.

CHARLES R. B. CLAFLIN.
